UNITED STATES PATENT OFFICE.

HERBERT RUFF, OF COLLINGSWOOD, NEW JERSEY.

AUTOMATIC CALENDAR.

Application filed November 21, 1924. Serial No. 751,207.

My invention relates to a new and useful clock controlled automatic calendar, adapted to show the correct date throughout the year, and adapted to change of the calendar face automatically every twenty four hours, and to effect such change in the calendar face reading, in a relatively short space of time, namely in a few seconds.

My invention relates more particularly to a clock controlled automatic calendar of the character stated above, which effects a substantially instantaneous change in the calendar face, every twenty four hours, effecting such change moreover always at the same particular instant during each succeeding twenty four hours, said changing instant being preferably 12 o'clock midnight.

My invention further relates to an automatic calendar which may be readily adapted to any common type of clock so that the automatic change of the calendar face will be controlled by the spindle or sleeve of the hour hand of the clock, without any more attention than is required by the ordinary eight day clock.

My invention further relates to a clock controlled automatic calendar which will indicate the regular sequence of days throughout any given year, with unvarying exactness, and regardless of the irregularity caused by varying number of days in the different months, or in a leap year.

With the above ends in view my invention consists of a novel calendar roll; comprising a continuous strip of some flexible material, such as paper and the like, having printed on one side thereof in regular sequence, a series of indicia indicative of each successive day of a particular year, and wound onto a roller or spindle.

My invention further consists of a series of setting or aligning apertures in said continuous calendar strip, properly located with respect to the successive calendar faces or indicia, and adapted to effect an accurate alignment of each of said successive calendar indicia with the calendar opening or window of the housing.

My invention further consists of a novel winding or reeling mechanism for said cal-

endar roll, adapted to unwind said roll from its spindle, means to normally retain said winding mechanism inoperative, clock controlled means to release said winding mechanism, and a stop mechanism registering and cooperating with said setting or aligning apertures in the calendar strip, for stopping the calendar strip as it is being unwound, so as to accurately align the next succeeding calendar indicia on said paper roll, with the calendar opening or window in the housing.

For the purpose of illustrating my invention, I have shown in the accompanying drawings forms thereof which are at present preferred by me, since they have been found in practice to give satisfactory and reliable results, although it is to be understood that the various instrumentalities of which my invention consists can be variously arranged and organized and that my invention is not limited to the precise arrangement and organization of these instrumentalities as herein shown and described.

Fig. 1 represents a front elevation of a clock controlled automatic calendar, embodying my invention, and including a conventional clock for controlling the same.

Fig. 2 represents a section on line 2—2 of Fig. 1.

Fig. 3 represents a front elevation the same as Fig. 1, with the front wall of the housing removed or omitted so as to expose to view the various mechanisms.

Fig. 4 represents a perspective view on an enlarged scale of the releasing and stopping mechanism.

Fig. 5 represents a section on line 5—5 of Fig. 4.

Similar numerals of reference indicate corresponding parts.

Referring to the drawings:—

1 designates my novel continuous calendar strip issuing from the roll 2, from which it is unwound periodically and intermittently every twenty four hours throughout the year. 95 The calendar roll 2 on the spindle or roller 3, is pivotally and rotatably mounted in the frame members 4 and 5, at its two ends respectively, and the calendar strip 1, passes over two vertically aligned horizontal guide 100

rollers 6 and 7, also rotatably mounted in the end plates or frames 4 and 5, and free to rotate. After passing over the two idler guide rollers 6 and 7, the strip 1 passes onto 5 the receiving roller 8, at the lower portion of the machine, to which receiving roller 8, the driving power is applied, so as to cause the same to draw the calendar strip 1 from the delivering roller 3, over the two idler 10 guide rollers 6 and 7 respectively, by passing a portion of said calendar strip 1 back of the front wall 9 of the housing, and parallel thereto, so as to expose to view a portion thereof, through the calendar opening 15 or window 10. The calendar strip 1, has printed thereon a series of successive indicia, preferably equally spaced with respect to each other indicative of each day of any particular year, arranged in the chronological 20 sequence of such days, beginning with the outer end of the calendar roll 2, and ending at the inner end of said calendar roll 2, and thus providing independent complete calendar faces along such strip, as illustrated by 25 the calendar face of "Monday, January 1st" shown in Figs. 1 and 3. The receiving roller 8, mounted on the spindle or shaft 11, is actuated and driven through a train of gears 12, 13, 14 and 15, by a flat coil spring 16 of 30 the type commonly used in clocks, said gears being rotatably mounted on parallel spindles or shafts 17 and 18 on the bearing plates or frame plates 5 and 19.

In order to retain the receiving roller inoperative, against the tendency of the driving spring 16 to rotate the same, through the train of speed change gears 12, 13, 14 and 15 as mentioned above I provide a ratchet wheel 20 on the receiving roller shaft 11, 35 fixedly secured thereto, and a pawl 21 pivoted at 22, and in operative alignment with the teeth 23 of said ratchet wheel. Thus, so long as the pawl 21 is in engagement with the teeth 23 of the ratchet wheel 20, the receiving 40 roller 8 will remain inoperative against the torque produced upon it by the spring 16, thereby retaining a particular portion of the calendar strip 1 motionless behind the calendar opening or window 10.

50 In order to release the pawl 21 periodically at a predetermined instant, namely at 12 o'clock midnight, I provide a novel release mechanism cooperating with said pawl, and cooperating with and controlled by the clock 24, indicated in outline in the Figs. 1, 2, and 3 having the hour hand spindle or sleeve 25 thereof shown in detail. The release mechanism consists of two vertical and overlapping flat release bars 26 and 27 respectively, joined together at their overlapping ends, by the two studs 28 and 29 fixed to the bars 26 and 27 respectively, and sliding freely in the elongated openings 29 and 30 in the corresponding portions of the 55 bars 27 and 26 respectively, thereby permit-

ting a slight and predetermined amount of longitudinal overlapping movement of the release bars 26 and 27 with respect to each other. The release bar 27 is pivotally secured to the pawl arm 31 at a point 32, 70 while the release bar 26, is pivotally secured at its upper end 33, to one side of a rocker arm 34, pivoted at 35. A gear 36 is secured to the hour hand spindle or sleeve 25, of the clock 24, and a second gear 37, having exactly twice the number of teeth on the gear 36, is rotatably mounted on the shaft 38 and is in mesh with the gear 36. The release cam 39 is fixed to the gear 37 and is in operative alignment with a follower end 40, of the 80 arm 41 of the belt crank lever 34 pivoted at 35. The cam 39 is provided along its outer periphery with a gradual rise from a "zero" point or position 42, to a "peak" point 43, from whence it takes an abrupt drop to the 85 "zero" point 42. The helical tension spring 44, acting on the arm 34, constantly urges the follower 40 against periphery of the cam 39, and also urges the release bar 26 downwardly. The release bars 26 and 27 are 90 provided with corresponding elongated openings 45. The release bar 26 carries a latch 46 hingedly secured thereto at a point 47 on the hinge 48, said latch passing through the elongated openings 45 in both bars 26 95 and 27, and adapted to swing into said elongated opening 45, due to gravity on said latch 46. The lower edge 49 of the elongated opening 45 in the release bar 27, however, is so located with respect to the pivot 47 100 and the lower edge 50 of the latch, as to permit said latch to fall into said elongated opening 45, only when the rod 26 is in its uppermost position with respect to the rod 27. Thus as the hour hand 51 makes two complete revolutions, namely records 24 hours; 105 the gear 37, and hence the cam 39 makes one complete revolution, namely moves from the "zero" point 42 on said cam, to the "peak" point 43, it forces down the follower point 40 against the tension of the spring 44, thereby raising the release bar 26 from the lower position to its uppermost position with respect to the release bar 27, and thereby permitting the latch 46 to fall into the opening 110 45 of the vertical release bar 27. When in this position, the lower edge 50 of the latch 46 being in alignment with the lower edge 49 of the slot 45 in the release bar 27, will prevent any relative overlapping movement between the two release bars 26 and 27, when the bar 26 is again lowered. Thus at the instant of 12 o'clock midnight when the "peak" point 43 passes the follower 40, said 115 follower, urged by the spring 44, rises abruptly to the "zero" point 42 of the cam 39, thereby forcing the release bar 26 downwardly, with the force of said spring 44. Since no relative or overlapping movement is then possible between the two release bars 26 and 120 27, the bar 26 is again lowered. Thus at the instant of 12 o'clock midnight when the "peak" point 43 passes the follower 40, said follower, urged by the spring 44, rises abruptly to the "zero" point 42 of the cam 39, thereby forcing the release bar 26 downwardly, with the force of said spring 44. Since no relative or overlapping movement is then possible between the two release bars 26 and 125 27, the bar 26 is again lowered. Thus at the instant of 12 o'clock midnight when the "peak" point 43 passes the follower 40, said follower, urged by the spring 44, rises abruptly to the "zero" point 42 of the cam 39, thereby forcing the release bar 26 downwardly, with the force of said spring 44. Since no relative or overlapping movement is then possible between the two release bars 26 and 130 27, the bar 26 is again lowered.

27 respectively, the bar 27, and hence the arm 31 of the pawl 21, is forced downwardly, thereby withdrawing said pawl 21 from engagement with the teeth 23 of the ratchet wheel 20. The ratchet wheel 20, thus released from the locking action of the pawl 21, at the instant of 12 o'clock midnight, permits the driving spring 16 to revolve the receiving roller 8 in the direction indicated by the arrow 52, thereby winding up the calendar strip 1 onto said roller 8 and withdrawing a corresponding length of the strip from the roller 2, so as to bring a new portion of said strip into alignment with the calendar window 10, in the front wall 9 of the calendar housing.

In order to prevent the strip 1 from unwinding entirely and also to stop the reeling action of the roller 8, after an exact length of the strip 1 corresponding to one date, has been unwound, and so as to accurately align the succeeding indicia on said strip, with the calendar window 10, I provide a novel locking mechanism cooperating with said release mechanism and said reeling or winding mechanism described hereinbefore, and controlled or governed by a series of setting or aligning openings or apertures 53 along one edge of the calendar strip 1, hidden from view by the front wall 9 of the housing, so as to be invisible from without. The apertures 53 in the calendar strip 1 are properly located with respect to each of the calendar indicia along the length of the calendar strip. The arm or finger 54 is mounted on a pivot 55, so as to be in alignment with said apertures 53, and is of a length sufficient to extend into said apertures when such apertures are brought into alignment therewith. A second arm 56, carrying a spring latch 57, is also secured to the pivot 55, so as to form a bell crank lever in combination with the first arm 54. The spring latch 57, best illustrated in the sectional view in Fig. 5, consists of the triangular latch block 57 carried by the flat spring 59, and is in alignment with an offset horizontal projection 58 at the lower end of the latch 46, when the release bar 26 and hence the latch 46 is in the lowermost position. In the normal stationary position of the calendar strip 1, shown particularly in Fig. 4, the arm or finger 54 urged by the spring 60, projects into the corresponding aperture 53 of the calendar strip and both of the arms 54 and 56 are thus normally held in their uppermost position, shown in Figs. 2 and 4, with the spring latch 57 in engagement with the projection 58 with the latch 46, so as to retain the same outside of the elongated opening 45 of the release bar 27. When, however, the release bar 26 is raised by the cam 29 as described hereinbefore, during a period of twenty-four hours, the latch 46 is also raised until the horizontal projec-

tion 58 thereof is raised above the spring latch 57, thereby permitting said latch 46 to fall into the elongated opening 45, so as to effect the subsequent releasing action, by the interlocking of the two release bars 26 and 27, as described hereinbefore. As the calendar strip 1 moves downwardly in the direction of the arrow 61 in Fig. 4, having been released by the simultaneously downward movement of the release bars 26 and 27, and the upper end of the particular aligning aperture 53, in the calendar strip 1, engages the end of the finger or arm 54 and lowers the same until the finger 54 is thus withdrawn from said aperture. The calendar strip 1 thereafter retains said finger or arm 54 in this depressed or lowered position. The downward movement or lowering of the arm 54, also lowers and withdraws the arm 56, and hence the spring latch 51 carried by said arm 56, so as to move the triangular latch block 57 past the horizontal projection 58 of the latch 46; which action is made possible by the yieldable spring support 59 of said triangular latch block 57. The calendar strip 1 continues to move downwardly in the direction of the arrow 61, to be wound onto the receiving roller 8, until the next succeeding aperture 53, corresponding to the next succeeding calendar indicia on said calendar strip 1, comes into alignment with the end of the arm 54. At that instant the end of the arm 54, urged by the spring 60, re-enters the succeeding aperture 53, raising the arms 54 and 56 into the position shown in Fig. 4, and thereby causing the triangular spring latch 57 to force and withdraw the latch 46, from locking engagement with the elongated opening 45 in the release bar 27, thereby breaking the locking action between the two release bars 26 and 27 and permitting the relative overlapping movement between the two release bars. The instant the latch 46 is thus withdrawn from locking engagement with the elongated opening 45 of the bar 27, the bar 27 being free to move upwardly relative to the bar 26, rises, due to the force of the spring 62, which is secured at its upper end to a support 63 fixed to the release bar 26, and thereby permits said spring 62 to raise the arm 31 and move the pawl 21 into operative locking engagement with a tooth 20 of the ratchet wheel 23, so as to lock the reeling mechanism in the particular position.

Thus by my novel automatic clock controlled calendar mechanism I may change the calendar reading substantially instantaneously and at any fixed and predetermined time during the twenty-four hours, although the changing point is preferably set to 12 o'clock midnight. The reeling mechanism while shown driven by coil spring 16, may be actuated through any other suitable means such as gravity devices, electric

motors or the like. The calendar strip 1 may be made of any suitable flexible material such as paper, parchment fabric, celluloid or the like, and if desired said strip may be 5 transparent or translucent. A source of light may be placed back of the calendar strip 1 so as to transmit the light through the transparent or translucent strip, thereby illuminating calendar face and bringing out 10 the calendar indicia in greater contrast.

It will now be apparent that I have devised a novel and useful automatic calendar which embodies the features of advantage enumerated as desirable in the statement of 15 the invention and the above description, and while I have, in the present instance, shown and described a preferred embodiment thereof which will give in practice satisfactory and reliable results, it is to be understood 20 that such embodiment is susceptible of modification in various particulars without departing from the spirit or scope of the invention or sacrificing any of its advantages.

Having thus described my invention, 25 what I claim as new and useful and desire to secure by Letters Patent, is:—

1. In an automatic calendar, a continuous 30 flexible strip, a series of indicia on said strip, indicative of the dates, and succeeding each other in chronological sequence, and a series of setting and aligning apertures in said strip, corresponding to and located with respect to said series of indicia.

2. In a device of the character stated, a 35 clock, a calendar roll, reeling mechanism adapted to unwind said calendar roll, means normally to retain said reeling mechanism stationary, means controlled by said clock for setting said reeling mechanism into motion, a series of setting and aligning apertures in said calendar roll, and a stop mechanism cooperating with said setting and aligning apertures, adapted to arrest the motion of said reeling mechanism.

40 3. In a device of the character stated, a calendar roll, a receiving roller parallel thereto for unwinding said calendar roll, means to impart a driving torque to said receiving roller, a ratchet wheel carried by said receiving roller, a pivotally supported pawl in operative alignment with said ratchet wheel, a means urging said pawl into engagement with said ratchet wheel, a lower releasing bar pivoted to the end of said pawl, an upper releasing bar overlapping said lower release bar and slidably secured thereto, a pivoted rocker arm having one arm thereof in operative engagement with the upper end of said upper release bar, a cam adapted to engage said rocker arm to thereby gradually raise said upper release bar during an extended period of time, and to abruptly lower the same at a predetermined instant, means intermediate 45 said cam and the spindle of the hour hand

of said clock for revolving said cam one revolution during every twenty four hours, and a means urging said arm against said cam and hence urging said upper release rod downwardly.

4. In a device of the character stated, a receiving roller, means to exert a constant torque on said roller, a ratchet wheel carried by said roller, a pivoted locking pawl in operative alignment with said ratchet wheel, means urging said pawl into engagement with said ratchet wheel, lower and upper release bars having their ends overlapping and slidably secured to each other, elongated openings through said bars, a latch hingedly secured to the upper release bar and extending through said elongated openings and tending to gravitate into said elongated opening in the lower release bar, an aligning finger, and a spring latch supported on a common pivot, a calendar roll, a calendar strip issuing from said roll and a series of aligning apertures in said calendar strip in alignment with said finger, adapted to actuate said spring latch by engagement with said finger so as to withdraw the gravity latch from the elongated opening.

5. In a device of the character described, 50 an upper and a lower release bar having their ends overlapped and slidably secured to each other, a gravity latch hingedly carried by the upper release bar, an aligning finger and spring latch carried by a common pivot, a horizontal projection carried by said gravity latch, in alignment with said spring latch in the lowermost position of the upper release bar.

6. In a device of the character described, 55 a reeling roller, means to exert a constant torque on said roller, a ratchet wheel carried by said roller, a pivoted locking pawl in operative alignment with said ratchet wheel, means urging said pawl into locking engagement with said ratchet wheel, release bars having their ends overlapping and slidably secured to each other, a latch carried by one of said release bars, means carried by the other release bar for engaging said latch so as to lock said release bars against any relative overlapping movement, an aligning and setting finger and a spring latch carried by a common support, a calendar strip, a series of aligning and setting apertures in said calendar strip in alignment with said finger, adapted to actuate said spring latch by engagement with said finger so as to throw said first latch out of locking engagement with respect to the release bars.

7. In an automatic calendar, a continuous 60 flexible strip, a series of indicia on said strip indicative of dates and succeeding each other in chronological sequence, and a series of positively interengaging, setting and

aligning means on said strip, corresponding to and located with respect to said series of indicia.

8. In a device of the character stated, a 5 clock, a calendar roll, reeling mechanism adapted to unwind said calendar roll, means normally to retain said reeling mechanism stationary, means controlled by said clock for setting said reeling mechanism into mo-

tion, a series of positively interengaging, 10 setting and aligning means on said calendar roll, and a stop mechanism coacting with said series of setting and aligning means by a positive interengagement therewith, 15 adapted to arrest the motion of said reeling mechanism.

HERBERT RUFF.
